J. B. HAY.
CANVAS BELTING.
APPLICATION FILED SEPT. 23, 1911.

1,022,080.

Patented Apr. 2, 1912.

UNITED STATES PATENT OFFICE.

JOHN B. HAY, OF YOUNGSTOWN, OHIO.

CANVAS BELTING.

1,022,080.

Specification of Letters Patent.

Patented Apr. 2, 1912.

Application filed September 23, 1911. Serial No. 650,958.

To all whom it may concern:

Be it known that I, JOHN B. HAY, a subject of the King of Great Britain and Ireland, residing at Youngstown, county of 5 Mahoning, and State of Ohio, have invented certain new and useful Improvements in Canvas Belting, of which the following is a specification.

My invention relates to belting for machinery and particularly to endless canvas belting.

The object of my invention is to provide an endless canvas belt formed of a plurality of laps or plies of such construction that 15 the several plies shall be securely interlocked.

A further object of my invention is to provide a belt as mentioned in which the heat which is always generated when belts 20 pass over small pulleys shall cause the parts or plies to more firmly lock or adhere to each other.

A further object of my invention is to provide a belt of the class mentioned which 25 shall more snugly hug the crown of the pulleys than belts of the usual construction.

A further object of my invention is to provide a belt formed of several plies and 30 of such construction that the oil and grease cannot work its way in between the edges of the several plies.

Other objects will appear hereinafter.

With these objects in view my invention 35 consists generally in a belt formed of a single strip of canvas of the proper width wrapped one ply upon the other until the desired thickness is obtained and in means for locking the ends of the strip into the 40 next adjacent ply.

My invention further consists in a belt characterized as above in which the first lap or layer is provided with integral lateral extensions which are folded over all of the other 45 laps with the exception of the last or outer lap, the edges of the extensions forming a butt joint throughout the length of the belt, and the outer lap being secured over said extensions, whereby all of the laps are se- 50 curely interlocked.

My invention further consists in a belt constructed as above stated in which the canvas is previously saturated or treated with balata gum and in which each of the 55 plies is secured in position separately by

hot pressing the same upon the previous plies.

My invention further consists in various details of construction and arrangements of parts all as will be fully described hereinafter and particularly pointed out in the claims.

My invention will be more readily understood by reference to the accompanying drawing forming a part of this specification 65 and in which—

Figure 1 is a plan view of a blank from which a belt is made embodying my invention in its preferred form, Fig. 2 is a perspective view illustrating the first lap in 70 position with the free end locked, and a portion of the second lap, Fig. 3 is a similar view illustrating all of the laps in position with the exception of the last, the extensions folded in and the last lap about to be 75 secured in position over the extensions, Fig. 4 is a plan view of a portion of the completed belt illustrating the manner of securing the outer end of the blank or strip, and Fig. 5 is a cross section on the line 80 $x-x$ of Fig. 4 drawn upon an enlarged scale.

The blank from which the belt is made comprises a strip 1 of canvas which is substantially the width of the completed belt 85 and of a length equal to the length the belt is to be times the number of laps of which it is to be composed. At one end the blank is formed with lateral extensions 2, each equal or slightly greater in width than half 90 the width of the belt and extending in length the distance of the length of the completed belt. The extensions 2 are integral with the body 1 of the blank and the portion of the blank or strip from which they extend 95 forms the first or inner lap of the device.

Extending from the first lap portion 3, and at the opposite end thereof from the long strip 1, is a short tongue 4 equal in width to that of the strip 1 and provided with lateral notches 5. Extending transversely of the body 1 adjacent the opposite ends of the extensions 2 is a slit 6 through which the tongue 4 is inserted to lock the first lap as shown clearly in Fig. 2. Adjacent the extreme opposite end of the body 1 are a pair of lateral notches 7, and at a distance therefrom equal to the length of the outer lap is a transverse slit 8 through which the end of the strip is inserted, locking the same in a 110

manner similar to that above described for the inner end or tongue 4. The length of the blank or strip 1 between the slits 6 and 8 is equal to the length of the belt times the 5 number of laps desired less two, the portion 3 forming the first lap and that between the notches 7 and slit 8 the last or outer lap.

In making the belt the canvas blank is first treated or impregnated with balata 10 gum. The tongue 4 is then inserted through the slit 6 as indicated in Fig. 2. This forms the first lap of the belt securely locked with the ends of the portions 2 abutting. The strip 1 is then wrapped around the first lap, 15 layer upon layer, until the belt is as thick as desired with the exception of one lap, each lap being hot pressed in position as it is wrapped about the first laps. The extensions 2 are then folded inwardly over the 20 several laps, with their edges abutting, and are hot pressed to secure them in position. The last lap is then wrapped in position over the extensions 2, the end inserted through the slit 8 and then hot pressed to 25 cement or secure the same.

It is obvious that with this construction the several plies of which the belt is composed are securely interlocked; the ends of the blank are locked into the next adjacent 30 lap, the portions 2 securely lock all of the laps together with the exception of the outer lap, and this outer lap locks the portions 2, thereby locking all together. Furthermore, 35 the heat generated while the belt is in use and running rapidly over the pulleys acts

upon the gum to more securely bind the parts together. It should also be noted that on account of the longitudinal seam at the abutting edges of the portion 2, the belt is adapted to curve more freely transversely to 40 hug the crown of the pulleys. Also the portions 2 prevent oil and grease from working in between the several plies which would tend to cause the same to separate and be otherwise objectionable.

45

Having described my invention what I claim as new and desire to secure by Letters Patent is:—

1. A belt of the class described, formed of a single strip of canvas wrapped longitudinally layer upon layer forming a plurality of plies and the free ends of said strip being locked into the next adjacent ply, substantially as described.

50

2. A belt of the class described, formed of a single strip of canvas wrapped longitudinally layer upon layer forming a plurality of plies, and provided with integral lateral extensions on the first ply, said extensions being folded over the edges of the succeeding plies and secured between the last ply and next to the last ply, substantially as described.

60

In testimony whereof I have signed my name to this specification in the presence of 65 two subscribing witnesses.

JOHN B. HAY.
